UNITED STATES PATENT OFFICE.

RICHARD F. LE BROcq, OF NEW YORK, N. Y., ASSIGNEE, BY MESNE ASSIGNMENTS, TO THE MOTION ADVERTISING CO., INC., A CORPORATION OF NEW YORK.

CONTROLLER.

1,068,672.

Specification of Letters Patent.

Patented July 29, 1913.

Application filed June 7, 1912. Serial No. 702,193.

To all whom it may concern:

Be it known that I, RICHARD F. LE BROcq, of New York, Kings county, New York, have invented a new and useful Improvement in Controllers, of which the following is a full, clear, and exact description.

My invention relates to improvements in controllers for electric current such as are used on elevator cars or the like.

10 The object of my invention is to produce a controller which can be operated in the ordinary way to regulate the current for stopping and starting the car, and to combine with a controller of this character 15 means for locking the controller so that it cannot be operated to stop or start the car except when the car is clear of a floor, or the door of the car is closed ready for starting. In other words, I provide an electro- 20 magnetic locking device which absolutely locks the controller when the car door is open, thus avoiding accidents occasioned by the premature starting of a car.

Another object of my invention is to 25 make the apparatus as simple and reliable as possible, and to arrange the locking means so that ordinarily it will not interfere with the free operation of the controller.

30 Reference is to be had to the accompanying drawings forming a part of this specification, in which similar reference characters indicate corresponding parts in all the views.

35 Figure 1 is a sectional front elevation of the controller showing my improvements. Fig. 2 is a cross section of the same, Fig. 3 is a diagrammatic view showing the circuit for the locking device, and giving also 40 a diagram of the several floors and the car.

In general appearance the controller is like the ordinary electric controller, and has the customary insulating back-plate 10 which has a box 11 covering the controller 45 mechanism, and a slot 12 through which the controller lever 13 projects and in which it swings, this lever having the customary insulating handle. The lever is preferably bent outward near its inner end as shown 50 at 14, and it is fulcrumed at 15 on the swinging arm 16 which turns on the pivot 17, and which is adapted to make contact with the contact points of the motor circuit as usual, and as referred to presently. The lever 13

is normally pressed inward toward the 55 plate 10 by a flat spring 18 which presses against the bulge 14 of the lever 13, and the spring is secured to a boss 19 on the lower part of the contact arm 16, and is stiffened and held taut against the lever 13 by a cot- 60 ter pin 20 which extends through the lugs 21 projecting forward from the contact arm 16 and straddling the lever 13. The lever carries near its upper end a contact roller 22 which engages the contact plate 23, and the 65 contact is kept close by the spring 18 above referred to. The contact arm 16 also has branching members 24 carrying contact rollers 25 which contact with the contact points 26 and 27 connecting with the motor 70 circuit, but I have not shown the motor circuit in this case because it has nothing to do with my present invention, which comprises the means for locking the lever and contact arm so that the lever and arm 75 cannot be swung except at the right time.

As frequently arranged in elevators, the movement of the lever 13 which brings the contacts 22 and 23 together, stops the motor, and a movement to the right or left so 80 as to bring the contacts 25 into engagement with the contacts 26 and 27, causes the motor to start so as to move the elevator up or down as desired. By having the contacts 22 and 23 in the position shown in 85 Fig. 2, the elevator cannot be started, and therefore I provide means for swinging the lever 13 on its axis 15, as a preliminary to moving the contact arm 16 to the right or left to start the motor. I have not given 90 the motor circuits, because these can be of any usual or preferred type, and have nothing to do with my invention, and moreover, to show all these circuits confuses my real invention which I have herein de- 95 scribed in detail.

In the lower end of the lever 13 and below the fulcrum 15, is a socket 28 which receives the end of a pin 29 held in the lower end of the contact arm 16, and it will be seen that 100 when the pin is in the socket the lever cannot be swung on its fulcrum 15, and the contact arm 16 cannot be swung on its fulcrum 17 because of the mechanism presently described. The pin 29 is normally pressed 105 out by a spring 30 which is coiled around it, and it is moved against the tension of the spring by the boss 31 on one arm of the

bell crank lever 32 which is arranged below the contact arm 16, and is fulcrumed as shown at 33 on the plate 34 which is secured to the insulating plate 10. The upper arm 5 of the bell crank 32 has ears 35 which straddle the boss 19 at the lower end of the contact arm 16, so that when the pin 29 is raised to lock the lever 13, the ears 35 will also lock the contact arm 16 to prevent it from swinging on its fulcrum 17. The lower arm of 10 the bell-crank 32 carries an armature 36 which swings opposite the electro-magnet 37, this being arranged within the box or casing 11.

15 The controller is arranged as usual on an elevator car 38 which moves opposite the several floors 39 in the ordinary manner, and the elevator well is provided with sliding doors 40 which can be of any approved 20 type and which open and close the entrance to the car 38 when the latter is opposite a floor.

In the elevator well at points opposite the sliding doors 40, are circuit breakers 41 25 which are placed in the path of the doors, so that when a door is closed, the circuit breaker will be actuated to break the circuit through the magnet 37 and unlock the lever 13 and contact arm 16, so that these parts 30 can be actuated to start the car; and after the car has left the floor, the circuit through the magnet will still be broken and remain broken until a door is opened.

The magnet 37 is included in a circuit 35 which has nothing to do with the motor circuit, and it can be conveniently connected up with the electric light wires of a building, or with any source of current supply. The circuit is as follows. From the battery 40 or source of supply A, through the wire a, the wires b, b¹, the circuit breakers 41, the wire c, the bracket 42 in the elevator well, the wire d which includes the magnet 37, and the wire a¹ back to the battery. The 45 bracket or support 42 is used so that the wire d can hang in a loop and permit the car to be raised and lowered without affecting the circuit.

It will be seen that when the circuit is 50 closed through the magnet 37, the armature 36 will be drawn toward the magnet, and the upper arm of the bell crank raised so as to lock the contact arm 16 and lever 13, but when the circuit is broken, the armature will 55 swing away from the magnet, the upper arm of the bell crank will drop, and the controller lever 13 be free to swing outward on its fulcrum 15 so as to break the contact at 22-23 and permit the lever and contact arm 60 to be swung so as to close the circuit as usual at the points 26 and 27. Thus it will be noticed that the controller cannot be operated, and the car cannot leave a floor, until the door 40 is closed so as to break the circuit 65 through the magnet.

When the elevator car 38 reaches a floor, the lever 13 is turned to the central position, thus stopping the elevator car, and when the door is opened, the circuit breaker 41 closes the circuit through the magnet 37, thus pulling 70 on the armature 36 and forcing the pin 29 into the socket 28 of the lever 13, thereby locking the lever and preventing any movement of the controller arm to start the car. When the door is again closed, the circuit 75 through the magnet is broken, and the lever 13 can then be swung on its axis 15 and moved to right or left to close a motor circuit and start the motor and elevator. Thus the opening of a door will close the circuit 80 through the magnet 37 and lock the lever 13 when it is brought to the central position. Consequently it will be seen that the car cannot be started except when the door is closed.

I have not shown the circuit breakers 41 85 in detail, but anyone skilled in the art will understand the form of circuit breaker to be used.

I claim:—

1. A controller comprising a swinging 90 contact arm arranged to make and break an electric circuit, a lever pivoted on the contact arm to swing at an angle to the axis of the contact arm, said lever being adapted to close and open the circuit of a motor, a 95 locking device to simultaneously lock the lever and the contact arm, electro-magnetic means for controlling the locking device, and circuit breakers in the circuit of the magnet. 100

2. The combination with an elevator car, the elevator well and the doors of the well, of a controller on the car having a swinging contact arm to close circuits for moving the car up and down, a lever pivoted on the 105 contact arm to swing at an angle to the contact arm, said lever being adapted to stop the motor of the elevator, a locking device to simultaneously lock the lever and contact arm, electro-magnetic means for controlling the locking device, and circuit breakers in the circuit of the magnet, said circuit breakers being arranged to operate by the opening and closing of the doors of the well. 110

3. A controller comprising a swinging contact arm arranged to make and break an electric circuit, a lever pivoted on the contact arm on an axis at an angle to the axis of the contact arm, a locking device to lock 120 the lever and contact arm together and to lock the contact arm against movement, electro-magnetic means for actuating the locking device, and circuit breakers in the circuit of the magnet. 115

4. A controller comprising an oscillating contact arm to make and break an electric circuit, a lever pivoted on the contact arm with its axis at an angle to the axis of the contact arm, a spring pressed slide 125 plate

mounted in the contact arm and entering a socket in the lever, an electro-magnet, an armature for the magnet arranged to move the locking pin against the tension of its 5 spring, and circuit breakers in the circuit of the magnet.

5. A controller comprising an oscillating contact arm arranged to make and break electric circuits, a lever pivoted on the contact arm with its axis at an angle to the 10 axis of the contact arm, said lever being also arranged to make and break an electric circuit, means for pressing the lever into a position essentially parallel with the contact arm, a locking device to lock the lever and contact arm together, means for locking 15 the contact arm against oscillation, an electro-magnet arranged to actuate both the aforesaid locking means, and circuit breakers 20 in the circuit of the magnet.

6. The combination with the oscillating contact arm and the lever swinging on the arm, of the spring pressed locking pin on the arm arranged to enter a socket in the 25 lever, a tilting bell crank arranged to lock the arm against movement and actuate the locking pin, an electro-magnet for tilting

the bell crank, and circuit breakers in the circuit of the electro-magnet.

7. The combination of the oscillating contact arm, the swinging lever carried by the 30 arm, and the spring pressed slide pin mounted in the arm and entering the socket in the lever, of a tilting bell crank arranged to contact with the pin and straddle the arm, 35 an electro-magnet for operating the bell crank, and circuit breakers in the circuit of the electro-magnet.

8. A controller comprising an insulating plate having a plurality of contacts thereon, 40 a contact arm oscillating on the plate and arranged to engage two of the said contacts, a lever fulcrumed on the contact arm and arranged to engage a third contact on the plate, a locking device to lock the lever and arm together and to lock the arm against 45 oscillation, electro-magnetic means for actuating the locking device, and circuit breakers in the circuit of the electro-magnet.

mounted in the contact arm and entering a socket in the lever, an electro-magnet, an armature for the magnet arranged to move the locking pin against the tension of its 5 spring, and circuit breakers in the circuit of the magnet.

5. A controller comprising an oscillating contact arm arranged to make and break electric circuits, a lever pivoted on the contact arm with its axis at an angle to the 10 axis of the contact arm, said lever being also arranged to make and break an electric circuit, means for pressing the lever into a position essentially parallel with the contact arm, a locking device to lock the lever and contact arm together, means for locking 15 the contact arm against oscillation, an electro-magnet arranged to actuate both the aforesaid locking means, and circuit breakers 20 in the circuit of the magnet.

6. The combination with the oscillating contact arm and the lever swinging on the arm, of the spring pressed locking pin on the arm arranged to enter a socket in the 25 lever, a tilting bell crank arranged to lock the arm against movement and actuate the locking pin, an electro-magnet for tilting

the bell crank, and circuit breakers in the circuit of the electro-magnet.

7. The combination of the oscillating contact arm, the swinging lever carried by the 30 arm, and the spring pressed slide pin mounted in the arm and entering the socket in the lever, of a tilting bell crank arranged to contact with the pin and straddle the arm, 35 an electro-magnet for operating the bell crank, and circuit breakers in the circuit of the electro-magnet.

8. A controller comprising an insulating plate having a plurality of contacts thereon, 40 a contact arm oscillating on the plate and arranged to engage two of the said contacts, a lever fulcrumed on the contact arm and arranged to engage a third contact on the plate, a locking device to lock the lever and arm together and to lock the arm against 45 oscillation, electro-magnetic means for actuating the locking device, and circuit breakers in the circuit of the electro-magnet.
